US00D646803S

(12) **United States Design Patent**
Jeong et al.

(10) **Patent No.:** **US D646,803 S**
(b4) **Date of Patent:** **** Oct. 11, 2011**

(54) **LED (LIGHT EMITTING DIODE) BULB**

(75) Inventors: **Sang Dong Jeong**, Incheon (KR); **Tae Gi Yoon**, Seoul (KR); **Jae Yeong Lee**, Seoul (KR)

(73) Assignee: **Amoluxe Co., Ltd.** (KR)

(**) Term: **14 Years**

(21) Appl. No.: **29/376,851**

(22) Filed: **Oct. 13, 2010**

(30) **Foreign Application Priority Data**

Apr. 15, 2010 (KR) 30-2010-0016718

(51) **LOC (9) Cl.** **26-04**

(52) **U.S. Cl.** **D26/2**

(58) **Field of Classification Search** D26/1-5,
D26/120, 138, 113; 313/313, 315, 316, 317,
313/318, 493; 315/52, 53, 56, 57, 58; 362/290,

(57) **CLAIM**

We Claim, the ornamental design for a LED (light emitting diode) bulb, as shown and described.

DESCRIPTION

FIG. 1 is a perspective view of the LED bulb showing our new design;

FIG. 2 is the front view thereof;

FIG. 3 is the rear view thereof;

FIG. 4 is the left side view thereof;

FIG. 5 is the right side view thereof;

FIG. 6 is the top view thereof; and,

FIG. 7 is the bottom view thereof.

1 Claim, 7 Drawing Sheets
